Primary Examiner — Lauren R Calve(74) *Attorney, Agent, or Firm* — Schultz & Associates, P.C.(57) **CLAIM**

The ornamental design for a cabinet knob, as shown and described.

DESCRIPTION

FIG. 1 is a front perspective view of a cabinet knob, shown independent of environment for ease of disclosure only;

FIG. 2 is a side elevation view thereof, shown independent of environment for ease of disclosure only;

FIG. 3 is a top plan view thereof, shown independent of environment for ease of disclosure only;

FIG. 4 is a bottom plan view thereof, shown independent of environment for ease of disclosure only; and,

FIG. 5 is a second perspective view of a cabinet knob, shown independent of environment for ease of disclosure only.

The broken lines shown represent environment and form no part of the claimed design.
